UNITED STATES PATENT OFFICE

2,109,134

SURGICAL APPLIANCE

Arthur B. Kendrick, East Orange, N. J., assignor
to James R. Kendrick Co., Inc., Philadelphia,
Pa., a corporation of Pennsylvania

Application October 30, 1936, Serial No. 108,437

3 Claims. (Cl. 2—239)

This invention relates to improvements in surgical appliances known as elastic stockings and elastic anklets constructed to be worn upon the leg and foot of a person suffering with varicose veins and other infirmities requiring surgical treatment.

Such appliances include in the construction thereof a tubular leg section and a tubular foot section formed of knit fabric having stretchable elastic strands inlaid in the body thereof, the sections being united in part and separated in part by a heel opening, and each section having a part which terminates in a heel edge at said opening.

15 In some instances the heel opening is not closed in the finished appliance, and in other instances, the heel opening is closed by a heel piece attached to the leg and foot sections and formed of fashioned knit fabric having no elastic strands inlaid therein and being much thinner than the fabric forming the said sections.

20 The present invention has particular relation to the form of the heel piece and to the relation of the parts thereof to the adjacent parts of the foot and leg sections and to the manner of attaching the heel piece thereto.

An object of the invention is to so construct and relate a part of the heel piece to an adjoining part of one of the said sections that the wall 25 formed by the fabric of the appliance will gradually expand in thickness from the thin fabric of the heel piece to the thicker fabric of the section to which it is attached, for smoothness of appearance and for ease and comfort in wearing.

Another object is to improve the connection of the heel piece with the leg section whereby the heel piece is extended to reinforce the leg section in the region above its heel edge, and whereby the 30 freedom of the heel piece and the adjacent portion of the leg section to adjust themselves to one another and to the wearer of the appliance is increased.

Another object is to improve the construction and relation of the parts of the appliance whereby various advantages are gained in wearing qualities and comfort for the user.

The invention resides in the novel construction, combination and relation of the parts as will be hereinafter described and claimed.

In the accompanying drawing, illustrating the invention,

Figure 1 is a side view of an elastic stocking embodying the invention, showing the free end

portions of the leg and foot sections turned slightly to illustrate the tubular formation thereof.

Figure 2 is a vertical section through the heel piece and leg section of the stocking, on line 2—2 of Fig. 1.

Figure 3 is a horizontal section through the heel piece and foot section of the stocking, on line 3—3 of Fig. 1.

Figure 4 is a side view, similar to Fig. 1, of the leg and foot sections of the stocking before the application of the heel piece thereto.

Referring to the drawing, the stocking comprises a tubular leg section 4, a tubular foot section 5, and a separately formed heel piece 6.

The leg section 4 and foot section 5 are united, 15 at 7, in the forward portion of the stocking, and they are separated by a heel opening 8, in the rearward portion of the stocking, at which the fabric of the leg section terminates in a heel edge 9, and the fabric of the foot section terminates 20 in a heel edge 10 which faces the edge 9.

The leg and foot sections 4 and 5 are formed of suitable knit fabric having stretchable elastic strands inlaid in the body thereof such, for example, as the fabric shown and described in my previous Patent No. 1,853,903, dated April 12, 1932; and, conveniently, the leg and foot sections 4 and 5 may be constructed like the leg and foot sections of the appliance illustrated and described in the said patent, the heel edges 9 and 30 10 of the present invention corresponding with the edges "10" and "11", respectively, of the appliance of the patent.

The heel piece 6 is formed of a single piece of suitable, plain knit fabric, having no elastic 35 strands inlaid in the body thereof. The heel piece may be produced on the well known circular knitting machine for producing stockings, and it comprises a heel portion 11, fashioned to fit the heel of the wearer of the appliance and to close 40 the heel opening 8, and an extension portion 12, fashioned to fit the adjacent part of the leg section 4 rising from its heel edge 9, and to occupy a position in close proximity thereto.

The extension portion 12 of the heel piece 6 is 45 preferably of gradually narrowing formation as it rises from the heel fitting portion 11 thereof, and the upper edge portion 13 of the heel piece 6 or its extension 12 is inturned and sewed to the fabric of the leg section 4 by a line of stitches 14 50 of zig-zag formation located a substantial distance above the heel edge 9 in spaced relation thereto, as clearly shown in Figs. 1 and 2.

The lower edge portion 15 of the heel piece 6 is a continuation of the upper edge portion 13 55

thereof, and it corresponds in length with and is fitted to the heel edge 10 of the foot section 5. The edge portion 15 is turned and sewed to the body of the heel piece 6 by a line of zig-zag stitches 16 in a manner to form a hem 17 which abuts against the heel edge 10 of the foot section 5 and is sewed thereto by a line of zig-zag stitches 18 forming a continuation of the line of stitches 14.

The fabric of the heel piece 6 is much thinner than the fabric of the foot and leg sections 4 and 5, and the thickness of the combined layers of the fabric forming the hem 17 is less than the thickness of the fabric of the adjacent foot section 5 to which it is attached, and, as the said hem is thicker than the fabric of the main body of the heel piece, a union between the heel piece and the foot section is provided in which the fabric of the appliance gradually expands in thickness from the thin fabric of the main body 20 of the heel piece to the thicker fabric of the foot section.

The extension portion 12 of the heel piece 6 reinforces the fabric of the leg section 4 in the region thereof, directly above the heel edge 9, which is subjected to considerable wear between the leg and shoe of the wearer of the appliance; and, as the fabric of the heel piece is much thinner than the fabric of the leg section, the fabric of the appliance is not objectionably increased in thickness in the reinforced area thereof, and such area has no objectionable fabric edge coupled with a line of stitches along the bottom of the reinforced area, as is the case in prior constructions wherein a reinforcing patch, in addition to the leg section and heel piece, has been sewed thereto.

The central part of the heel edge 9 of the leg section is tacked or sewed to the fabric of the heel piece by several stitches 19 in spaced relation to the ends of the edge 9 to prevent accidental upward folding or rolling of the fabric of the leg section directly over the edge 9 when the appliance is in service, and such tacking leaves the major portion of edge 9 free from the fabric of the heel piece 6 to permit free play between the heel piece 6 and the heel edge 9 and the fabric of the leg section 4 directly above the edge 9, and thereby permit them to adjust themselves to one another and to the wearer of the appliance when it is in service.

By extending the heel piece 6 well above the heel edge 9 of the leg section 4 and attaching the heel piece to the leg section by the line of stitches 14 which are located a substantial distance above the heel edge 9, instead of terminating the heel piece at the heel edge 9 and attaching it to said edge, the leg section 4 at and in the region of said edge is left free to expand and contract without interference from the means which attaches the heel piece to the leg section, thus giving free action to the fabric of the leg section at and in the region above the heel edge 9 where it is most needed.

I claim as my invention:

65 1. A surgical appliance comprising a tubular

leg section, a tubular foot section, and a separately formed heel piece, each of said sections being formed of knit fabric having stretchable elastic strands inlaid in the body thereof, the forward portions of said sections being united and the rearward portions thereof being separated by a heel opening at which a portion of the fabric of each section terminates in a heel edge facing the heel edge of the other section, and said heel piece closing said opening and being formed of fabric which is thinner than the fabric of said sections and extending above the heel edge of the leg section and having the lower edge of the leg section unattached to the heel piece throughout a portion of the lower edge of the leg section, means for attaching the upper edge portion of the heel piece to the leg section in spaced relation to the heel edge thereof, and means for attaching the lower edge portion of the heel piece to the foot section.

2. A surgical appliance comprising a tubular leg section, a tubular foot section, and a separately formed heel piece, each of said sections being formed of knit fabric having stretchable elastic strands inlaid in the body thereof, the forward portions of said sections being united and the rearward portions thereof being separated by a heel opening at which a portion of the fabric of each section terminates in a heel edge facing the heel edge of the other section, and said heel piece closing said opening and being formed of fabric which is thinner than the fabric of said sections and extending above the heel edge of the leg section and having the lower edge of the leg section unattached to the heel piece throughout a portion of the lower edge of the leg section, means for attaching the central portion of the heel edge of the leg section to the heel piece, means for attaching the upper edge portion of the heel piece to the leg section in spaced relation to the heel edge thereof, and means for attaching the lower edge portion of the heel piece to the foot section.

3. A surgical appliance comprising a tubular leg section, a tubular foot section, and a separately formed heel piece, each of said sections being formed of knit fabric having stretchable elastic strands inlaid in the body thereof, the forward portions of said sections being united and the rearward portions thereof being separated by a heel opening at which a portion of the fabric of each section terminates in a heel edge facing the heel edge of the other section, and said heel piece closing said opening and being formed of fabric which is thinner than the fabric of said sections and which has a turned edge portion sewed to the body thereof and forming a hem having an edge which abuts the heel edge of one of said sections and is sewed thereto, and means for attaching the heel piece to the other of said sections, the thickness of the combined layers of the fabric forming said hem being less than the thickness of the fabric to which it is sewed.

ARTHUR B. KENDRICK. 65
